J. W. HEADLEY,
RESILIENT WHEEL.
APPLICATION FILED DEC. 3, 1919.

Patented July 20, 1920.

2 SHEETS—SHEET 2.

UNITED STATES PATENT OFFICE.

JOHN W. HEADLEY, OF LONG BEACH, CALIFORNIA.

RESILIENT WHEEL.

1,347,034.

Specification of Letters Patent.

Patented July 20, 1920.

Application filed December 3, 1919. Serial No. 342,159.

To all whom it may concern:

Be it known that I, JOHN W. HEADLEY, a citizen of the United States, residing at Long Beach, in the county of Los Angeles and State of California, have invented certain new and useful Improvements in Resilient Wheels, of which the following is a specification, reference being had to the accompanying drawings.

10 This invention relates to certain improvements in resilient wheels, and it is an object of the invention to provide a device of this general character with novel and improved means whereby the same effectually absorbs 15 the shocks and jars incident to the travel of the vehicle to which it is applied.

It is also an object of the invention to provide a novel and improved wheel of this general character wherein the shock absorbing 20 agencies comprise a plurality of suitably mounted springs coacting with both the hub and the felly of the wheel structure.

The invention consists in the details of construction and in the combination and arrangement of the several parts of my improved resilient wheel whereby certain important advantages are attained and the device rendered simpler, less expensive and otherwise more convenient and advantageous 30 for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view partly in side elevation and partly in section of a 40 wheel constructed in accordance with an embodiment of my invention;

Fig. 2 is a fragmentary sectional view taken through the structure, as illustrated in Fig. 1;

Fig. 3 is a fragmentary sectional view 45 illustrating a modified form of my invention, and,

Fig. 4 is a fragmentary sectional view illustrating a still further modified form of 50 invention.

As disclosed in the accompanying drawings, H denotes a hub, preferably of wood, and provided at one end with a reduced extension 1. Snugly fitting to and extending 55 around the periphery of the hub H is an annular member or band 2, provided with two

transversely spaced and circumferentially disposed series of cups or pockets 3.

Surrounding the hub H, and substantially concentric thereto when the wheel is free of load, is an annular member 4 of a width substantially equal to the combined length of the hub H and extension 1 thereof. The inner face of the member 4 is provided with the cups or pockets 5 substantially in radial alignment with the cups or pockets 3. Interposed between the hub H and the member 4 is the shock absorbing agency herein disclosed as comprising a plurality of expansible members 6, preferably coil springs. Each of said members or springs 6 has one end portion seating within a cup or pocket 3 of the hub H, and its opposite end portion seating within the cup or pocket 5 of the member 4, and substantially in radial alignment with the first named cup or pocket 3.

The extension 1 has also snugly engaged therearound an annular member 7 provided with the circumferentially spaced cups or pockets 8 in radial alignment with the supplemental cups or pockets 9 carried by the adjacent side portion of the annular member 4. Seating within the pockets 8 and 9 are the expansible members or coil springs 10, which provide a further shock absorbing agency for the member 4.

Side plates 11 extend inwardly from the sides of the member 4, and are provided with the annular grooves 12, to receive the edges of the member 4.

The plates 11 are held to the member 4 by the clamping bolts 14, coacting therewith, and extending transversely of the structure. An intermediate portion of each of the plates 11 extends inwardly, as at 15, and 95 contacts with the outer face of the member 4, and from said portion 15 the plate 11 extends outwardly a predetermined distance.

Secured to each of the plates 11, preferably by the bolts 14, is the inner marginal 100 portion of a bracing or reinforcing plate 16, which extends inwardly, and is secured to the outer marginal portion of the plate 11 by the bolts 17, and which bolts also connect the outer portions of both of the plates 11. 105 The reinforcing plates 16 have their outer portions 18 extending beyond the plates 11, with the opposed faces of said portions 9, and in parallelism in cross section. Fitting between the portions 18 is the felly 19. Suitably secured to the side faces of the felly 19 are the annular plates 20, preferably of

brass, which have sliding contact with the annular plates 21, preferably of steel, carried by the opposed faces of the portions 18. The coaction of the plates 20 and 21 is such as to materially facilitate the relative movements between the felly 19 and the hub H, or the member 4.

Interposed between the felly 19 and the member 4 is a shock absorbing agency disclosed as comprising a plurality of circumferentially spaced expandable members or coil springs 22. One end of each of the springs 22 seats within a cup or pocket 23, carried by the outer face of the member 4, and the opposite end of said member or spring seats within a pocket or recess 24, carried by the inner face of the felly 19. The felly 19 has mounted thereon a tire T, which may be of metal, hard rubber or of any character preferred. As the structure of the tire T in itself forms no particular part of my invention, a detailed description thereof is believed to be unnecessary.

The central opening defined by the outer plate 11 has disposed thereover a hub cap 25, suitably fixed to said plate 11.

In the form of my invention, as particularly illustrated in Fig. 3, the hub H' has coacting therewith only a single series of springs 6', and only a single reinforcing or bracing plate 16'.

In the embodiment of my invention, as particularly illustrated in Fig. 4, the portions 18^a of the side plates 11^a have arranged therebetween a supplemental annular member 26, normally substantially concentric to the member 4^a. Interposed between the member 4^a and the member 26 are the circumferentially spaced expandable members or coil springs 27. Interposed between the member 26 and the felly F is another series of circumferentially spaced expandable members or coil springs 28. This latter construction is particularly adapted for use in connection with wheels of a materially large diameter. The outer edges of the portions 18^a of the plates 11 provide annular shoulders 29, with which the felly 19 contacts for limiting the inward movement of said felly between the portions 18. This same structure is present in the two modified forms of construction herein described and illustrated.

From the foregoing description it is thought to be obvious that a resilient wheel constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying

out my invention in practice except as hereinafter claimed.

I claim:

1. A resilient wheel structure comprising, in combination, a hub provided with an extension at its outer end, an annular member surrounding said hub and spaced therefrom, said annular member also surrounding the extension of the hub, a cushioning agency interposed between the annular member and the hub, a cushioning agency interposed between the annular member and the extension of the hub, side plates carried by the annular member and extending inwardly thereof, said plates also extending outwardly of the annular member, a felly positioned between the outwardly extending portions of the side plates, cushioning means interposed between the annular member and the felly, brace plates secured to the side plates and to the outer marginal portions of the outwardly extending parts of the side plates, said brace plates extending beyond the peripheries of said side plates, and annular plates secured to the opposed faces of the extended portions of the side plates and with which the felly has sliding contact.

2. A resilient wheel structure comprising, in combination, a hub provided with an extension at its outer end, an annular member surrounding said hub and spaced therefrom, said annular member also surrounding the extension of the hub, a cushioning agency interposed between the annular member and the hub, a cushioning agency interposed between the annular member and the extension of the hub, side plates carried by the annular member and extending inwardly thereof, said plates also extending outwardly of the annular member, a felly positioned between the outwardly extending portions of the side plates, cushioning means interposed between the annular member and the felly, brace plates secured to the side plates and to the outer marginal portions of the outwardly extending parts of the side plates, said brace plates extending beyond the peripheries of said side plates, and annular plates secured to the opposed faces of the extended portions of the side plates, and annular plates secured to the side faces of the felly and having contact with the plates secured to the extended portions of the brace plates.

3. A resilient wheel structure comprising, in combination, a hub provided with an extension at its outer end, an annular member surrounding said hub and spaced therefrom, said annular member also surrounding the extension of the hub, a cushioning agency interposed between the annular member and the hub, a cushioning agency interposed between the annular member and the extension of the hub, side plates carried by the annular member and extending inwardly thereof, said plates also extending outwardly of the

annular member, a felly positioned between the outwardly extending portions of the side plates, cushioning means interposed between the annular member and the felly, brace
5 plates secured to the side plates and to the outer marginal portions of the outwardly extending parts of the side plates, said brace plates extending beyond the peripheries of said side plates, annular plates secured to the
10 opposed faces of the extended portions of the side plates, and annular plates secured to

the side faces of the felly and having contact with the plates secured to the extended portions of the brace plates, said last named plates being of a thickness less than the 15 thickness of the peripheral portions of the side plates whereby shoulders are provided to limit the inward movement of the felly.

In testimony whereof I hereunto affix my signature.

JOHN W. HEADLEY,
